UNITED STATES PATENT OFFICE.

ROBERT LAURIN, OF CHICAGO, ILLINOIS.

SWITCH-OPERATING DEVICE.

1,323,700.

Specification of Letters Patent.

Patented Dec. 2, 1919.

Application filed July 21, 1917. Serial No. 182,036.

To all whom it may concern:

Be it known that I, ROBERT LAURIN, a citizen of the United States, residing at Chicago, in the county of Cook and State 5 of Illinois, have invented certain new and useful Improvements in Switch-Operating Devices, of which the following is a specification.

My invention relates to railway switch 10 operating devices and has as its primary object to provide an improved device of this character which will be simple in its construction, inexpensive to manufacture and which will be reliable in its operation.

15 In devices of this character it is desirable to provide visual signals to indicate the position of the switch, and also to provide locking means whereby the switch may be locked in its open or closed position. When 20 switching railway cars from one track to another, it frequently happens that a car is moved too far on the side track and, consequently, is forced through the closed switch at the opposite end of the side track.

25 If the switch is locked in its closed position with the usual positive lock, a car being forced through the switch will very likely be derailed unless the connection between the switch and switch operating mechanism

30 should become bent or broken in a manner to permit the switch rails to move from one position to another when engaged by the flange of the car wheel. If the connection between a switch and its operating means

35 be bent or broken by reason of a car being forced through the switch points while the switch is closed, the switch points will not assume their former position after the car has been moved a distance sufficient to clear 40 the switch, and the visual signal being operatively connected with the switch operating mechanism, instead of being connected directly to the movable rails of the switch, will not correspond with the position of the

45 said movable rails. For the purpose of minimizing the number of car derailments and other railway accidents resulting from defective mechanism in switch operating devices, my invention contemplates a novel 50 locking means for switch operating devices

which will yield under the strain incident to the forcing of a car through a closed switch, for example, so as to prevent the connection between the switch and operating mechanism from being damaged. The invention also provides a suitable connec-

tion between the visual signal and the signal operating mechanism, whereby the visual signal is positively operated to indicate the assumed position of the switch each time 60 that the switch rails are moved from one position to another. In the event that such movement of the switch rails is accidental, such for example, as when a car is forced through a switch while the switch is closed, 65 the visual signal will be moved to indicate the actual position of the switch and the said switch and signal will be automatically locked in such position.

Another common objection to the various 70 forms of switch operating devices is that the collection of foreign matter, such, for example, as snow and ice, prevents the proper operation of the device. In order to overcome these objections it has been 75 proposed to inclose the operating parts in a casing. This practice, however, is also objectionable, for the reason that the casing makes the device more expensive to manufacture. A further and more important 80 reason for this objection is that the casing prevents the operating parts from being readily inspected and also makes it more difficult to repair the parts when such repairs are necessary.

85 One of the specific objects of my invention is to overcome the above objections by providing a switch-operating device consisting of a minimum number of parts which are so constructed and arranged that 90 the operation of the device will not be affected by the collection of foreign matter.

The invention consists in the novel arrangement, construction and combination of parts hereinafter described and claimed 95 for carrying out the above stated objects and such other incidental objects as may appear from the following description:

The preferred embodiment of my invention is illustrated in the accompanying 100 drawings, in which like characters of reference designate like parts, and in which

Figure 1 is a plan view of a railway switch showing a switch operating device constructed in accordance with my invention.

Fig. 2 is an end view, in elevation, of the operating device illustrated in Fig. 1.

Fig. 3 is a view, in perspective, illustrating the construction of a slide and cam 110 member employed in my preferred construction.

Fig. 4 is a longitudinal sectional view taken on line 4—4 of Fig. 1.

Fig. 5 is a plan view of the structure shown in Fig. 4, viewing the same from the 5 under side and illustrating the manner of locking the device.

Fig. 6 is a fragmentary view, similar to Fig. 5, illustrating the manner in which the lock is bent when a car accidentally passes 10 through the switch in the direction indicated by the feathered arrow in Fig. 1.

Fig. 7 is a cross-sectional view taken on line 7—7 of Fig. 4; and

Fig. 8 is a vertical section taken on line 15 8—8 of Fig. 1.

Referring to the drawings, 10 and 11 designate railroad rails which are permanently secured to cross ties 12 and which constitute a portion of the main track. 13, 20 14 designate movable rails constituting a switch adapted to coöperate with the permanent rails in a manner well understood by mechanics familiar with railway switch construction. The movable rails are slidably supported on tie plates 15 in the usual manner and are held in spaced relation with respect to each other by means of the spacing bars 16, 16. The spacing bars are secured to attaching 25 lugs 17, 17^a, consisting of members having rail base engaging jaws 18 secured to the movable rails and provided with tongues or guides 19 which extend under the base flange of the permanent rails 10 and 11. 30 These tongues hold the movable rails down against the tie plates 15 when the switch is being moved to either its "open" or "closed" position.

In connection with the form of operating 40 device illustrated in the drawings, I preferably provide a strong connection between the switch and operating device so as to prevent said connection from being bent or broken in a manner to make the switch 45 operating device inoperative. With this view in mind I have provided the attaching lug 17^a with a connecting rod 20, formed so as to avoid any sharp bends which would likely weaken the same and formed at one 50 end with a clevis 20^a to provide suitable means for flexibly connecting said rod with the operating device. The operating device consists of a base member 21 adapted to be secured to the outer 55 end of the ties 22, 22 and formed with suitable guideways 23 for a slide 24 which is connected with the connecting rod 20. The top side of the slide 24 is provided with spaced lugs 25, 26 which engage the 60 cam surfaces 27, 28, respectively, of a spiral-shaped cam 29. The cam 29 is rotatably supported between upstanding webs 30, 31 on the base 21 by means of the bolt 32 and is preferably provided with a wide hub 33 65 which bears against the inner surfaces of

said upstanding webs to prevent any lateral movement of the cam. When the operating handle 34 of the cam 29 is moved from the full line position shown in Fig. 1 to the position indicated in dotted line in the same 70 figure, the slide 24 and connecting rod 20 are reciprocated to move the switch to its open position. The switch is locked in its open or closed position by means of latch bars 35, 36, which are pivoted on the base 75 member 21 so as to drop by gravity into operative engagement with the vertical shoulders of the lugs 37, 38, respectively. The lugs 37, 38 are formed on the under 80 side of the slide 24 so as to prevent the collection of foreign matter, such, for example, as snow and ice, from interfering with the proper operation of the latch bars 35—36. These lugs are also formed with tapered 85 surfaces 39, 40 to permit the latch bars to 90 ride over the lugs when the slide 24 is moved from one position to another. The desired 95 adjustment of the switch may be effected by properly positioning the washers 41 on the latch bar pivots 42, 43, so that the latch 100 bars will not drop into their respective operative positions until the movable rails 13, 14 have been drawn tightly against the rails of the main track in a manner to completely close or open the switch, as the case 105 may be. A visual signal 44 is rigidly secured to a staff 45 which is supported in a vertical position in a bearing 46. A pin 47 is screwed into the lower portion of the staff 45 and extends through a spiral slot 48 110 formed in the bearing 46. By this construction, any vertical movement of the staff 45 will impart a rotational movement to the signal 44 and thereby move the same to the 115 signaling position corresponding to the 105 actual position of the switch. 49 designates a cam rigidly secured to the slide 24 so as to move therewith and slidably engage the lower end of the staff 45 so as to elevate the same to the position indicated in Fig. 110 8 of the drawings. This position is intended to indicate that the switch is closed. When the slide 24 is moved in the direction indicated by the arrow in Fig. 8, the staff 45 and signal 44 will be lowered by the 115 action of gravity and assume a signaling position indicating that the switch is open. When it is desired to move the switch 120 from the closed position shown in Fig. 1 to the open position, the latch bar 35 is 125 raised to the dotted line position indicated in Fig. 2 and the operating handle 34 turned to the position indicated in dotted lines on Fig. 1. The rotational movement imparted to the cam 29 causes the slide 24 to be moved in the direction indicated by the feathered 125 arrows in Figs. 4, 5 and 8. During such movement of the slide 24 the inclined surface 40 of lug 38 will tilt the pivoted latch bar 36. When the slide 24 has moved the 130

required distance to completely open the switch; the latch bar 36 will drop to its locking position adjacent the vertical shoulder of said lug 38. The movement of the slide 24 and cam 49 during the opening operation of the switch causes the visual signal to be operated in the manner above set forth so as to indicate the open position of the switch. The spiral surfaces 27, 28 of the cam 29 are formed with a pitch sufficient to permit the handle 34 to be automatically moved to the dotted line position of Fig. 1 when sufficient force is imparted to the slide 24, such as would be the case if the switch 10 should be accidentally forced from one position to another. In order to permit a free sliding movement of the slide 24 so as to impart a rotating movement to the cam 29 and also prevent the connecting rod 20 from being subjected to severe strains when the switch is accidentally moved, the latch bars 35, 36 are made of wrought iron so that they will bend to the position shown in Fig. 6. By permitting the free movement of the slide 24 when the switch is accidentally moved the visual signal 44 will be automatically changed to indicate the actual position and the switch locked in its assumed position in substantially the same manner 20 as when the device is operated by hand. When the switch is operated in a manner to cause either of the latch bars 35 or 36 to be bent, as above described, the bent portion of the latch will be wedged between one of the lugs on the under side of the slide 24 and the lug 21^a on the under side of the base 21 in a manner which will make it difficult to return the switch to its former position without first removing the bent latch bar.

40 I claim:

1. A device for operating a railway switch, comprising a slide, a cam for operating said slide, means for connecting said slide to said switch, and yieldable locking means associated with said slide adapted to be bent to lock said switch in its open or closed position when the switch has been automatically moved from one position to another.

50 2. A device for operating a railway switch, comprising a slide, a cam for operating said slide, means for connecting said slide to said switch, and gravity operated means associated with said slide for locking said switch in its open or closed position.

3. A device for operating a railway switch, comprising a slide, a cam for operating said slide, means for connecting said slide to said switch, and gravity operated yieldable means associated with said slide for locking said switch in its open or closed position.

60 4. A device for operating a railway switch, comprising a slide, a cam for operating said slide, means for connecting said

slide to said switch, and gravity operated means engaging the under side of said slide to lock said switch in its open or closed position.

5. A device for operating a railway switch, comprising a slide, a cam for operating said slide, means for connecting said slide to said switch, and gravity operated yieldable means engaging the under side of said slide to lock said switch in its open or closed position.

6. A device for operating a railway switch, comprising a slide provided with spaced lugs, a cam operatively engaging said lugs adapted to oscillate said slide, means for connecting said slide to said switch, and gravity operated means engaging the under side of said slide to lock said switch in its open position.

7. A device for operating a railway switch, comprising a slide provided with spaced lugs on the top side and with spaced abutments on the under side thereof, means connecting said slide with said switch, a spiral cam operatively engaging the spaced lugs on said slide to move the same to open and close said switch, and gravity operated latch bars adapted to coöperate with the spaced abutments on the under side of said slide to lock the switch in open or closed position as desired.

8. In a device for operating a railway switch, the combination with movable railroad rails constituting a switch, of a slide provided with spaced abutments on the under side thereof, means for connecting said switch with said slide, means for oscillating said slide, latch bars adapted to engage said abutments to lock said switch in its operative position, and means associated with said latch bars for effecting an adjustment of said switch.

9. In a device for operating a railway switch, the combination with movable railroad rails constituting a switch, of a slide provided with spaced abutments on the under side thereof, means for connecting said switch with said slide, means for oscillating said slide, gravity operated latch bars adapted to engage said abutments to lock said switch in its operative position, and means associated with said latch bars for effecting an adjustment of said switch.

10. In a device for operating a railway switch, the combination with movable railroad rails constituting a switch, of a slide, means connecting said slide with said switch, means for operating said slide so as to open or close said switch, and manually releasable means associated with said slide for locking said switch in its open or closed position, said locking means being yieldable to permit said device to be operated when said switch is moved accidentally from one position to another.

11. In a device for operating a railway switch, the combination with movable railroad rails constituting a switch, of a slide, means connecting said slide with said switch, 5 means for operating said slide so as to open or close said switch, and manually releasable, gravity operated latch bars associated with said slide for locking said switch in its open or closed position, said latch bars being yieldable to permit said device to be operated when said switch is moved accidentally from one position to another.

12. In a device for operating a railway switch, the combination with movable railroad rails constituting a switch, of means 15 for opening and closing said switch, and manually releasable, gravity operated latch bars for locking said switch in its open or closed position; said latch bars being adapted to be bent should the switch be moved from one position to another without said bars being released from their locking position.

13. In a device for operating a railway switch, the combination with movable railroad rails constituting a switch, of means 25 for opening and closing said switch comprising a slide, a visual signal, a cam adapted to slidably engage said signal to operate the same, and manually releasable, gravity operated latch bars for locking said switch in its open or closed position; said latch bars being adapted to be bent, should the switch be moved from one position to another, without said bars being released from their locking position.

14. In a device for operating a railway switch, the combination with movable railroad rails constituting a switch, of means 40 for opening and closing said switch comprising a slide, a visual signal, a cam carried by said slide and adapted to slidably engage said signal to operate the same, and manually releasable, gravity operated latch 45 bars for locking said switch in its open or closed position; said latch bars being adapted to be bent, should the switch be moved from one position to another, without said bars being released from their locking position.

15. In a device for operating a railway switch, the combination with movable railroad rails constituting a switch, of means comprising a slide for opening and closing 55 said switch, a visual signal for indicating the position of said switch, comprising a staff, a support formed with a cam slot and adapted to support said staff in a vertical position, a pin secured to said staff and ex-

tending into said cam slot whereby the vertical movement of said staff causes the same to rotate, and means for operating said signal comprising a cam on said slide adapted to slidably engage the lower end of said staff.

16. In a device for operating a railway switch, the combination with movable railroad rails constituting a switch, of means comprising a slide for opening and closing said switch, a visual signal for indicating 70 the position of said switch, comprising a staff, a support formed with a cam slot and adapted to support said staff in a vertical position, a pin secured to said staff and extending into said cam slot whereby the vertical movement of said staff causes the same to rotate, and means for operating said signal simultaneously with the operation of said switch comprising a cam on said slide adapted to slidably engage the lower end 80 of said staff.

17. A device for operating a railway switch, the combination with movable railroad rails constituting a switch, of means comprising a slide for opening and closing 85 said switch, a visual signal for indicating the position of said switch comprising a staff, a support formed with a cam slot and adapted to support said staff in a vertical position, a pin secured to said staff and extending into said cam slot whereby the vertical movement of said staff causes the same to rotate, means for operating said signal simultaneously with the operation of said switch comprising a cam on said slide adapted 90 to slidably engage the lower end of said staff, and means for locking said switch and signal in their operative positions.

18. A device for operating a railway switch, the combination with movable railroad rails constituting a switch, of means comprising a slide for opening and closing said switch, a visual signal for indicating the position of said switch comprising a staff, a support formed with a cam slot and 100 adapted to support said staff in a vertical position, a pin secured to said staff and extending into said cam slot whereby the vertical movement of said staff causes the same to rotate, means for operating said signal 105 simultaneously with the operation of said switch comprising a cam on said slide adapted to slidably engage the lower end of said staff, and gravity operated means engaging the under side of said slide to lock said 110 switch and signal in their operative positions.

ROBERT LAURIN.
